UNITED STATES PATENT OFFICE.

SAMUEL E. DITTMAN, OF NEW YORK, N. Y.

PRINTING-PLATE.

1,128,665.

Specification of Letters Patent. Patented Feb. 16, 1915.

Application filed August 28, 1913. Serial No. 787,114.

To all whom it may concern:

Be it known that I, SAMUEL E. DITTMAN, a citizen of the United States, and a resident of New York, in the county of New York and State of New York, have invented certain new and useful Improvements in Printing-Plates; and I do hereby declare that the following is a full, clear, and exact description thereof, reference being had to the accompanying drawings, and to the letters of reference marked thereon, which form a part of this specification.

This invention relates to a novel means applicable for use in the process or method 15 of reproducing pictures in their original or natural colors, and especially a method of coloring black and white reproductions of pen and ink sketches, wash drawings, oil paintings, photographs, or any subject calling for the use of a color or colors.

In carrying out my novel method for printing in several colors only one printing plate, that is to say, an original half-tone or other relief plate, herein referred to as the 25 image or key-plate, is employed for making a print or impression in black or any other color. For making other color impressions a relief plate having uniformly disposed, minute elevations or points, adapted for 30 printing a flat tint when inked and applied to the paper with uniform pressure, is employed in connection with an overlay or overlays, prepared from the key-plate, and adapted to give an impression or impressions 35 from the flat tint relief plate, corresponding with the form and thickness of the parts of the overlay or overlays. The said image or key-plate is prepared in the usual manner, familiar to those skilled in 40 the art. For making such overlay a print or proof is taken from the key-plate on a sheet of paper or like thin, flexible material. The several printed impressions are used in the preparation of a series of overlays, one 45 for each of the different colors to be employed. Such overlays may be prepared by any of the processes heretofore used in making overlays, in such manner that the areas of the impressions on the overlay sheet, 50 which are to be printed in a certain color, are so treated that the said sheet in such areas is made thicker than other parts of the sheet; the increased thickness varying on different parts of the overlay sheet ac-

cording to the depth of tone desired. As for 55 instance, this result may be accomplished according to a process heretofore employed for making overlays by the use of prints or proofs taken from an image or key-plate, the same consisting in applying ink or some 60 adhesive material to the areas of the impression in which the color is to be printed, and then applying to the sheet while the ink or adhesive material is still in a sticky condition, a powdered material, which is caused 65 to adhere in a greater quantity or thickness to the parts of the impression to be printed in darker shade, and in a less quantity or thickness to the parts to be printed in lighter shade, so that the sheet so treated has an 70 added thickness of pulverized material imparted to it, varying according to the depth of shade of the color to be printed by the use of the overlay. The overlay may also be prepared in other ways, as for instance, it 75 may be a chalk overlay, or a cut paper overlay.

For the purposes of illustration, I will describe my novel device as applied in a process used for printing in the three primary 80 colors, namely, red, yellow and blue. Each color is printed by a separate impression and by the use of an overlay prepared for that color, as above described, in connection with a half-tone granular or similar flat tint relief plate; the surface-structure of said plate being similar to that of the half-tone relief printing plates used in the art, but having uniformly distributed printing points or elevations, so that it will give an impression, 85 uniform in depth or shade, under uniform pressure. The overlay, made of varying thickness in its different parts, in accordance with the desired color areas and depth of tone to be given to the different parts of 90 such color areas, is applied in the usual manner to the tympan sheet of the press. When the sheet to be printed is pressed against the inked surface of the flat-tint plate, the areas of the paper corresponding with the thickest 95 parts of the overlay are, through the action of said overlay, subject to the greatest pressure between the tympan and the flat-tint relief plate, and therefore receive a strong or heavy ink impression, while the areas of 100 the paper corresponding to the unthickened or thinner parts of the overlay sheet receive no impression from the inked plate, or are 105

subject to a light pressure giving a proportionally light ink impression. For printing in several colors the printing operation is repeated by the use of each color overlay, the 5 several impressions being made to register with each other and with an impression made from the original or key-plate, or a duplicate of the same. It will of course be understood that secondary or tertiary colors 10 may be produced by superposing two or all three, of their respective component primary colors in the required depths of shade. I do not, however, wish to limit the scope of my invention to the use of the key-plate itself 15 in this printing operation, nor to any definite number of color impressions to be thus superposed. Nor do I limit myself to the order in which the color impressions and the key-plate impressions are printed, as the 20 order of making the impressions may be reversed or interchanged without affecting the results obtained.

The features of my invention may be better understood by reference to the accompanying drawings, in which:

Figure 1 shows the impression from a key or image printing plate, adapted for printing an entire picture in black or a single color; Fig. 2 shows an overlay sheet containing an impression from the key-plate; Fig. 3 is a face view of the overlay sheet, as prepared for printing one color; Fig. 3^a shows the overlay in section, taken on line 3^a—3^a of Fig. 3; Fig. 4 shows in plan view 30 a flat-tint half-tone point or dot surface plate, with a portion thereof greatly magnified; Fig. 5 is a sectional view of a half-tone point or dot surface greatly magnified; Fig. 6 is a plan view of a granular flat-tint 35 surface with a portion thereof greatly magnified; Fig. 7 is a sectional view of a half-tone dot surface, with alternating high and low points, greatly magnified; Fig. 8 illustrates the tone-effects produced in printing 40 with varying pressure on a half-tone dot surface, having alternating high and low points, greatly magnified.

The impression A (Fig. 1) is such as may be printed from a half-tone or other 50 relief plate (not shown) prepared by the usual process of photo-engraving. The area marked *a* in said impression A represents a part or area of the picture which is to receive an additional impression in one color.

Figs. 2 and 3 illustrate the method of 55 making the color-overlay sheet. Fig. 2 shows the overlay sheet B after it has received an impression from the key-plate, and Fig. 3 shows the same after the application thereto of adhesive material and powdered substance, to increase the thickness of the sheet, in the area *b*, intended to be printed in a single color and corresponding with the area *a* in Fig. 1. Fig. 3^a shows 60 the same overlay sheet in section, after the

pulverized material has been applied thereto, so as to increase the thickness of the sheet, in the area *b* corresponding with the area *a* of the key-plate impression. It will be understood that several overlay sheets prepared as described, and arranged in superposed relation, so as to form several layers and to give additional thickness at the thickened parts, may be used as the overlay 70 in the making of either impression in the 75 printing operation.

Figs. 4 to 7 illustrate various surface structures of flat tint relief plates adapted for use in carrying out my process. Figs. 4 and 5 show the ordinary half-tone dot 80 surface, C, magnified, consisting of minute, tapered or pyramidal projections *c*, called points or dots, of uniform height and placed uniformly equidistant in intersecting rows. Such surfaces have usually from 175 to 200 85 points or dots to the linear inch. Fig. 6 illustrates the magnified surface of a granular flat-tint plate, having a uniformly roughened surface of irregular elevation and depression corresponding approximately in 90 fineness to the 200-dot half-tone plate. Fig. 7 shows a surface with alternating high points *d* and low points *e*, such as would correspond to a 100-dot surface when printing only the high points *d* and a 200-dot surface when printing both the high points *d* and low points *e*.

The high and low dot flat-tint plate above described is particularly adapted to be used in my process, as it gives a wide range of gradation in shade or depths of color with but slight variation of pressure. Fig. 8 illustrates a few of the gradations, in magnified proportions, of the impression received from such high-and-low dot surface, varying in degree of depth of color in proportion to the pressure given to the overlay. F shows the result of printing with such light pressure that the points *d* only of the 100 sheet come in contact with corresponding dots *d* of the printing surface; G shows the effect of printing with sufficient pressure to depress the paper into contact with the alternate low dots *e*, producing the light dots *e'* alternating with the heavier dots *d'*. 105 H shows the effect of printing with sufficient pressure to produce a nearly solid tone or color; and J shows the effect obtained by printing with sufficient pressure to produce a solid color. To produce the best results I 110 have found it preferable to provide a specially prepared flat-tint plate of such suitable depth that the paper may easily reach bottom for solid color. In other words, in such a specially prepared plate the projections *c* (Fig. 5) or *d* and *e* (Fig. 7) are made relatively low, and the depressed portions therebetween shallow, so that it does 115 not require excessive pressure on the paper to produce a solid color impression there- 120

upon. There is no limit, however, to the variety of such flat-tint surfaces which are adaptable to my process without deviating from the fundamental principles of my invention. Neither is my invention restricted to the material used for the printing plate or surface, and such surface may be either elastic or rigid.

In printing a picture or the like by the use of the image or key-plate and a plurality of overlays, the color-impressions are made to register with the impression from the key-plate. Each color impression is made by inking the flat-tint plate and pressing the paper against said plate through the action of the overlay, so that the impression will correspond with the overlay both as to location of the color areas and the shading of the same. When pressure is applied to the sheet to be printed, with the overlay held in position between the tympan and the flat-tint plate, it is evident that the presence of the added thickness in the area of the overlay produces such pressure in the thickened area of said sheet as is necessary for making the color impression.

In printing with the overlay as described, the printing paper may receive a colored ink impression from some parts of the flat-tint plate and no impression from other parts of such plate, or it may receive an impression varying in depth or shade in its different parts according to the thickness of the corresponding parts of the overlay. The impression from the original key-plate, or duplicate of the same, will usually be made in black or dark ink and will show in outline or otherwise the entire subject shown by the picture, while the completed print will have all of the desired colors localized and shaded as desired.

My device herein described may be further extended to be used in connection with any of the present methods of color-printing for the additional building up of areas which may be light in a print from the key-plate, but which it is desired to make heavier in the case of one or more of the additional colors. The flat-tint plate is neutral for any subject, and can be inked in any color, so it may be used with any number of separate overlays, made from a key-plate

not exceeding the same in size, until it is worn out.

I claim as my invention:

1. In the art of printing, means for producing impressions, comprising a printing surface provided with a plurality of series of points or projections differing in height and each consisting of points or projections of the same height, which are uniformly arranged with respect to each other; the points constituting the several series being uniformly distributed in interspersed relation to each other.

2. In the art of printing, means for producing impressions, comprising a printing surface provided with high and low points or projections alternately arranged and spaced equidistantly apart, said plate being adapted to produce a variation of dot impressions by the variation of pressure upon the material receiving the impression.

3. In the art of printing, means for producing impressions, comprising a plate having a printing surface provided with uniformly and alternately arranged high and low points or projections in which the depressions between said points or projections are relatively shallow, said plate being adapted to produce a variation of dot impressions varying in depth from faint to solid by relatively slight variations of pressure upon the material receiving the impression.

4. In the art of printing, means for producing impressions, comprising a flat tint relief plate having a printing surface provided with high and low points or projections spaced equidistantly apart and arranged in intersecting rows, said plate being adapted to produce a wide variation of impressions with a slight variation of pressure upon the material receiving the impression.

In testimony, that I, claim the foregoing as my invention I affix my signature in the presence of two witnesses.

SAMUEL E. DITTMAN.
